UNITED STATES PATENT OFFICE.

WILLIAM G. DUNN, OF CLARINDA, IOWA.

FENDER BRACE.

Application filed December 1, 1924. Serial No. 753,287.

This invention relates to that class of modified form of the lower clamping member. Referring to the accompanying drawings, a connecting rod attached to each clamping member and extended across the automobile from one fender to the other, and a tension means applied to the connecting member for supporting the fenders under tension to prevent them from rattling and to enable them to withstand such downward pressure as is frequently subjected to them without distorting them from their properly alined positions. The upper fender clamping member is indicated generally by the reference numeral 11. It is made of a single piece of strap metal. Its central portion is shaped to fit the contour of the fender to which it is to be applied. Its outer end is formed with a hook shaped portion 12 to extend under the fender flange, and its inner end is provided

The objects of my invention are to provide a fender brace of this class of simple, durable and inexpensive construction that may be manufactured in quantities of cheap and inexpensive and easily obtainable material, with a minimum of machine work, to thereby produce an efficient and durable fender brace at a minimum of expense. with a substantially horizontal extension 13 having a vertical opening throughout. The lower clamping member 12 is also formed of a single piece of strap metal and comprises a flat body portion 14 with a downwardly extended gripping jaw 15 at one end and an upwardly extended gripping jaw 16 at the other end. It is provided

More specifically it is my object to provide a fender brace of this character which may be readily, quickly and easily adapted 25 for fenders of different sizes and spaced apart different distances. with an opening to receive the connecting rod hereinafter described, but this opening is arranged nearer the gripping jaw 16 than the gripping jaw 15 as clearly shown in Figure 2, for purposes hereinafter made clear. 80

A further object is to provide improved means for connecting together and adjustably locking the inner ends of the fender supporting rods. The connecting rod is indicated generally by the reference numeral 17 and is formed of a piece of metal rod having its inner end 85 notched at its top, as shown by the reference

My invention consists in the construction, numeral 18, and having its outer end bent arrangement and combination of the various parts of the device, whereby the objects contemplated are attained, as hereinafter more fully set forth, pointed out in my claim, and illustrated in the accompanying drawings, in which:

Figure 1 shows a top or plan view of the rear end of an automobile showing my improved fender brace applied to the rear fender thereof. The brace 20 comprises a body portion 21. In its sides near each end are two inclined slots 22, and 95 slidably mounted in each pair of slots is a rod 23 having heads formed on its ends at

Figure 2 shows an enlarged, detail, perspective view illustrating one end portion of my improved fender brace. The dotted lines in this figure indicate the position of the fender within the clamping members. 24 to prevent longitudinal movement of the rods, which rods are herein referred to as wedge rivets.

Figure 3 shows a side elevation of my improved fender clamping members and a portion of a connecting rod attached thereto illustrating the clamping members in their open position ready to receive a fender and before being clamped thereto.

55 Figure 4 shows an enlarged, detail, perspective view illustrating the means for adjusting the tension of the connecting rods. 110

Figure 5 shows a perspective view of a

members 11 are placed on top of the fenders with the rods 17 extended through the openings in the parts 13 thereof. Then the lower clamping member is swung to position with its relatively short end toward the fender and its relatively long end extended inwardly as shown in Figure 2, and in order to conveniently and quickly grip the fender, each of the rods 17 is elevated at its inner end, as shown in Figure 3, so that the lower gripping member will stand widely spaced apart from the upper gripping member. Then when the rods 17 have their inner ends moved downwardly, the lower gripping members will be moved upwardly to engage the fender, as shown in Figure 2. When these two rods 17 are in approximately horizontal positions, then the tension member is applied thereto by inserting the ends of the rods through the ends thereof under the wedge rivets, then the rods are drawn together until the proper tension is applied, whereupon the wedge rivets will lock the rods firmly together.

Assuming, however, that the device is to be applied to a fender of less width, then the operator simply removes the lower tension member from the rod 17 and turns it upside down and re-applies it to the rod 17 and places the long end thereof in position to engage the fender, as shown in Figure 3.

In the event that it is desired to apply the device to fenders that are spaced more widely apart than usual, then it is only necessary to provide a new tension member of greater length, and all of the other parts may be utilized as originally made.

The device as illustrated in Figure 2 may be used without changing on almost all sizes and shapes of fenders, but in the event that an unusual size is presented, my device may be adapted very readily and quickly and with a minimum expense to any form or size of fender.

The only parts of my fender brace that require any special care in the manufacture are the upper clamping member and the connecting rods, which must be notched at one end. These can be standardized for all sizes and shapes of fenders and widths of

the car between the fenders. The reversible lower clamping member gives two adjustments and is sufficient for ordinary purposes, but if desired, new lower clamping members may be provided very quickly and cheaply, and may be made without special tools or machinery in any machine or blacksmith shop.

In the modified form shown in Figure 5, I have shown a lower clamping member with one jaw only, which may be substituted for the clamping member having a clamping jaw at each end.

I claim as my invention:

An improved fender brace comprising an upper clamping member formed of strap metal and designed to be placed on top of a fender and formed with a hook at its outer end to pass under the edge of the fender and formed with an extension at its inner end having an opening through it, a lower clamping member made of strap metal and arranged under the inner end of the upper clamping member and formed with a jaw extended downwardly and outwardly and also formed with an opening adapted to register with the opening in the first named clamp member, a connecting rod having its end extended downwardly and then outwardly and designed to be passed through the registering openings in both clamping members, said parts being so arranged that as the inner end of the rod is moved downwardly, the lower clamping jaw is moved upwardly toward the upper clamping member, said lower clamping member being formed with an extension projected in a direction opposite from the clamping jaw and extended upwardly and then inwardly and being of a length from the said opening different from the length of the clamping jaw and designed to be engaged by the said rod so that as the inner end of the rod moves downwardly it will engage said extension and aid in forcing the gripping jaw upwardly as the rod moves downwardly, and also so that the said gripping member may be reversed to adapt it for fenders of different widths.

Des Moines, Iowa, November 7, 1924.

WILLIAM G. DUNN.
